UNITED STATES PATENT OFFICE

ALBERT ADOLPH SIGMUND BARKER, OF SOUTHCHURCH, ENGLAND

POCKET COMB

Application filed September 8, 1930. Serial No. 480,553.

The present invention relates to an improved pocket comb of the type in which metal teeth insulated from one another are in circuit with an electric battery carried in the handle, the circuit being completed through the scalp or skin of the user.

According to the present invention, sets of teeth having a sinuous shape are mounted on bars moulded into a back which also serves 10 as a handle of a phenol condensation product.

The invention is more particularly described with reference to the accompanying drawings in which:—

Figure 1 is a sectional end view on the line 15 AA of Figure 4 of a comb according to the present invention.

Figure 2 is a corresponding sectional elevation.

Figure 3 is a section on the line BB of Figure 2.

Figure 4 is an outside view.

The comb consists of a plurality of prongs 1 bent into sinuous shape in order to impart a wave to the hair of the user. These teeth are 25 mounted in two grooves upon bars 2, 3, and insulated from one another by being incast or inmoulded into a handle or comb back 4 of ebonite or a phenol condensation product. This handle is hollow to receive an electric 30 battery 5 having contacts 6, 7, at its ends engaging with the ends of compression springs 8, 9, the opposite ends of which are out-turned to form a brush 11 extending through a slot in the end of the casing 4, and adapted to each 35 contact with one end of one of the bars 2, 3, to complete an electric circuit through the prongs of one bar 2 through the spring 9, battery 5, spring 8 and the other bar 3.

The ends 11 of the springs 8, 9 are maintained in the slots by means of the end caps 40 12 and 13, detachably screwed on to the hollow handle 3 to allow renewal of the battery 5.

I declare that what I claim is:—

1. A comb comprising in combination a 45 hollow body of insulated material, a pair of comb bars each having groups of prongs mounted thereon, and moulded into said insulating material, a detachable battery within said body, compression springs engaging 50 contacts at each end of said battery, extension

parts on the end of each spring each adapted to engage one end of one bar.

2. A comb comprising in combination a hollow body of insulated material, a pair of comb bars each having groups of prongs 55 mounted thereon, and moulded into said insulating material, a detachable battery within said body, compression springs engaging contacts at each end of said battery, extension parts on the end of each spring each adapted 60 to engage one end of one bar and locking caps closing each end of said hollow body.

3. A comb comprising in combination a hollow body of insulated material, a pair of comb bars each having groups of sinuous 65 prongs mounted thereon, and moulded into said insulating material, a detachable battery within said body, compression springs engaging contacts at each end of said battery, extension parts on the end of each spring 70 each adapted to engage one end of one bar.

In witness whereof, I have hereunto signed my name this 28 day of August, 1930.

ALBERT ADOLPH SIGMUND BARKER.
